UNITED STATES PATENT OFFICE.

MAX RUBIN, OF BROOKLYN, NEW YORK.

GARMENT-BUCKLE.

931,802.

Specification of Letters Patent. Patented Aug. 24, 1909.

Application filed November 13, 1908. Serial No. 462,382.

To all whom it may concern:

Be it known that I, MAX RUBIN, a citizen of the United States, and resident of the city of New York, borough of Brooklyn, in the 5 county of Kings and State of New York, have invented certain new and useful Improvements in Garment-Buckles, of which the following is a specification.

This invention relates to improvements in 10 garment buckles.

The object of my invention is to provide a new and improved buckle of this class which is simple in construction, strong, and absolutely reliable in action and prevents slipping of the webbing when the buckle is closed, both when the strain on the webbing is in a direction parallel with, or approximately parallel with the plane of the buckle, as well as when the strain is in a plane transversely to the buckle or on an angle to the buckle, all without cutting, perforating, or in any other way injuring or damaging the webbing.

In the accompanying drawings in which like numerals of reference indicate like parts in all of the figures, Figure 1 is a face view of one construction of my improved garment buckle, opened. Fig. 2 is a vertical central transverse sectional view through the same, 25 on an enlarged scale, showing the manner of applying the buckle to the webbing and the manner of holding the webbing when the buckle is closed. Fig. 3 is a vertical transverse sectional view of a slightly modified 30 construction of the buckle, the webbing being in place and the buckle opened. Fig. 4 is a similar view of these same parts, the buckle being closed. Fig. 5 is a face view of the blank for making the clamping lever of 35 my improved buckle.

My improved buckle is composed of two parts, one part being the frame and the other part being the webbing clamping lever pivoted to the frame, this lever being provided 45 on its inner face with a longitudinal shoulder, which, when the web clamping lever is swung down, presses the web resting upon the bottom member of the frame, upon this bottom member and thereby securely clamping the 50 webbing between the shoulder and the bottom member of the frame. To increase this clamping action and to permit the bottom member of the frame to yield more or less when the web clamping lever is swung down, 55 the bottom member of the frame may be formed of yielding spring arms which under

normal tension contact at their free ends, and can be spread under the clamping strain produced by the shoulder upon the web resting on said bottom member. The buckle 60 can also be made with the bottom piece of the frame made continuous and rigid.

The web clamping lever 1 which is provided, preferably at its center with the projecting finger 2, is preferably struck up from a sheet metal blank shown in Fig. 5. This blank 3 is provided with projecting end parts 4 which form the end of the main body of the lever and adjacent to these parts 4 the ends of the blank are recessed as at 5, the 65 part of the metal between 5 and 5 being curved as shown in the drawings when the blank is bent upon itself. Beneath the parts 5 there is a lug 6 on each end, each lug being provided with a recess 7. Beneath 70 the lug 6 there is a tongue 8 which is bent over on the dotted line to form the clamping face of a shoulder. The metal of the blank 75 is doubled over on itself and curved between the points 5 as stated, and then the end 80 lugs 6 are bent rectangularly so that their outer edges will now rest against the inner surface of the main body portion of the clamping lever. The recesses 7 in the lugs 6 form 85 openings for receiving the pivots of the web holding frame 12 which is provided with an opening 13 through which the web can be passed, as shown in Figs. 3 and 4. In the construction shown in Figs. 1 and 2, the holding frame 12 is formed of bent wire which 90 passes through the holes formed by the notches 7 in the ends of the shoulder part and extends lengthwise through the shoulder part and the free ends of the wire forming the frame butt at the center of the frame as 95 shown in Fig. 1 and are curved at 15, whereby the bottom cross piece of the web holding frame is made yielding so that it can give downward in the direction of the plane of the buckle and also can give laterally. 100 As shown in Figs. 3 and 4 the body 14 of the frame is formed of a solid piece of metal and the pivots 25 project through the holes formed by the notches 7.

The webbing 16 is passed through the opening 13 of the web holding frame from the rear, the front forming a loop 17 which is stitched by stitches 18 for the purpose of attaching and holding the frame to the webbing. The running end of the webbing, that is to say, 110 the free end which is to be secured in place, after the webbing has been set at the pre-

determined size, is then passed through the opening 13, and over the loop part 17 in said opening and is then locked in place by pressing or turning downward the clamping lever. For example, if the buckle is used on suspenders the clamping lever is opened and the entire buckle is moved up or down until it has reached the desired place and then the buckle is closed. For a belt, or a garter, the web is adjusted in a similar way. When the clamping lever is swung from the raised position, shown, for example, in Figs. 1 and 3 to the closed positions, shown in Figs. 2 and 4, the shoulder also swings down and its outer edge or corner first comes in contact with that part 19 of the webbing that extends over loop 17 and as the locking lever is swung down the corner of the shoulder gradually presses this part 19 of the webbing downward and upon the webbing resting upon the bottom cross piece of the frame, and when the clamping lever is pressed downward until it rests flat upon that part of the webbing beneath the part 19, at the front, the shoulder on the clamping lever is in complete contact with the web part 19 and presses this part 19 upon the looped part 17 and in turn presses this part 17 upon the bottom cross piece of the frame, whereby the running part 19 of the webbing is clamped firmly and securely and in such a manner that it cannot yield in any direction, between the shoulder and the bottom part of the frame.

To insure greater clamping action and to permit of using the buckle with webs of greater variations in thickness, the bottom of the frame is made to form two spring arms so that, as the locking lever is swung down and the shoulder of the clamping lever is pressed upon the webbing, this lower member of the frame can give more or less. When the angle of the shoulder begins to

press upon the part 19 of the webbing, the bottom part of the frame is forced down and thereby the ends of the two spring arms are separated a greater or less distance, but as the locking lever is swung down completely so that the shoulder rests upon the web part 19 the spring arms of the frame contract slightly under their spring tension and thus assist materially in clamping the running part of the webbing between the shoulder and the bottom part of the frame.

Having described my invention what I claim as new and desire to secure by Letters Patent is:

1. In a garment buckle, the combination with a web holding frame, of a clamping lever pivotally mounted on the frame, said clamping lever being bent up from sheet metal to have a longitudinal flat web clamping shoulder, formed by bending the bottom part of the sheet metal of the lever laterally, then upward and then inward to the inner face of the lever, substantially as set forth. 65

2. In a garment buckle, the combination with a web holding frame, of a clamping lever on the same, said clamping lever being bent up from sheet metal to have a longitudinal web clamping bent portion formed by bending the bottom part of the metal lever laterally, then upward and then inward to and against the inner face of the lever, said bent portion having apertured ends formed of sheet metal lugs bent from the ends of the said upwardly bent part, substantially as set forth. 70 75

Signed this 11th day of November A. D. 1908.

MAX RUBIN.
